FLOATING ROOF

Fred L. Goldsby and Clifford M. Orr, Chicago, Ill.,
assignors to Chicago Bridge & Iron Company,
a corporation of Illinois

Application February 6, 1946, Serial No. 645,867

7 Claims. (Cl. 220—26)

1

This invention relates to a floating roof for use in a floating roof tank.

Floating roof tanks are used for storing volatile liquids. In these tanks the roof floats on top of the liquid and rises and falls as the quantity of liquid is increased and decreased. Various types of floating roofs have been proposed in the past for use in tanks of this type. Many of the roofs, however, were too heavy or difficult to construct, and some would not maintain themselves level on the surface of the liquid, especially when subjected to loads of rain water, snow, and the like, or to the pressure of wind.

We have invented a floating roof that is relatively light-weight and that maintains its level on top of the liquid at all times. The new roof functions efficiently even under a load of snow, and provisions are made for draining water from the roof, even in cases of very heavy rainfall. The new floating roof comprises a deck, a substantially centrally located pontoon beneath said deck, and radial pontoons also beneath said deck extending from the central pontoon.

The invention will be described as related to the embodiment shown in the accompanying drawings. Of the drawings Fig. 1 is a plan view, partially broken away for clarity of illustration, of a floating roof tank employing the new floating roof; and Fig. 2 is a vertical section taken along line 2—2 of Fig. 1.

The floating roof tank comprises an outer substantially cylindrical shell 18 and a floating roof 11 therein adapted to float on top of the contents of the tank. The floating roof is positioned within the shell and has a narrow space 12 between the edge of the roof and the shell. Any type sealing means (not shown) may be used between the roof and the shell.

The floating roof 11 has a deck 13 essentially flat but sloping slightly downwardly toward the center. Around the edge of the deck there is located a vertical rim 14 extending above and below the deck. Beneath the deck 13 there are located a central pontoon 15 and radial pontoons 16 with the radial pontoons being substantially evenly spaced around the roof and extending from the central pontoon 15 to the rim 14. As shown each radial pontoon 16 is of substantially triangular shape with the apex being adjacent the central pontoon 15. Adjacent sides 17 of adjacent pontoons are substantially parallel and the central pontoon 15 is formed of partitions 18 connecting the apex of one radial pontoon to the next apex.

In the center of the roof there is provided a

2

drain 19 extending from the lowest portion of the deck 13 through the central pontoon 15. Any water that falls on the deck will run to the center of the deck and be drawn off through the drain 19.

5 In the floating roof as shown any vapors formed will gather under the deck 13 and will form a substantially annular vapor space 20 around the outer edge of the deck. Escape of the vapors will be prevented by the downwardly extending portion of the rim 14.

10 In order to equalize vapor pressure within the vapor spaces 20 between pontoons 16 a substantially horizontal pipe 21 is provided extending through each pontoon and communicating with the vapor spaces under the deck of the roof adjacent the pontoon. The pipes have their outlets near the decks so as to be in communication with the vapor as soon as formed. Such pipes are not 15 absolutely necessary but are preferred in order that the roof will float level at all times.

20 Having described our invention as shown in the accompanying drawings, it is our intention that the invention be not limited by any of the details of the description unless otherwise specified, but rather be construed broadly within its spirit and scope as set out in the accompanying claims.

We claim:

1. A floating roof for a floating roof tank comprising a deck sloping toward the center, a central polygonal pontoon beneath the deck, a drain at substantially the center of the roof and extending through the central pontoon, a depending rim at the outer edge of the deck, and a plurality of substantially evenly spaced triangular pontoons beneath the deck extending from the central pontoon to the rim, the apex of each of said triangular pontoons being at one of the apices of the central pontoon, adjacent sides of adjacent triangular pontoons being parallel to each other and being widely spaced to provide a substantial vapor space therebetween.

2. The floating roof of claim 1 wherein a vapor passageway is provided extending through each pontoon and communicating with the vapor spaces on either side of said pontoon.

3. A floating roof for a floating roof tank comprising a circular, substantially flat throughout the top thereof, single deck sloping slightly toward the center, a depending peripheral rim at the outer edge of the deck, means forming with said deck a centrally located pontoon therebeneath, and means forming with said deck spaced pontoons therebeneath radiating outwardly from the central pontoon to the rim with the portions

of the deck between the last mentioned pontoons forming gas retaining spaces beneath the deck.

4. The floating roof of claim 3 wherein there is provided a drain at substantially the center extending through the central pontoon.

5. The floating roof of claim 3 wherein the radial pontoons are triangular and are substantially equally spaced around the roof, adjacent sides of adjacent pontoons being substantially parallel to each other.

6. The floating roof of claim 3 in which the central pontoon is polygonal and the radial pontoons are triangular with the apex of each triangle at one of the apices of the polygon.

7. The floating roof of claim 3 in which adjacent sides of adjacent radial pontoons are substantially parallel to each other. 15
